[57] CLAIM

The ornamental design for a combined dispensing nozzle and cap for a pressurized container, as shown and described.

DESCRIPTION

FIG. 1 is a perspective view of a combined dispensing nozzle and cap for a pressurized container showing my new design;

FIG. 2 is a left side elevational view thereof, the right side view being a mirror image of the left side shown;

FIG. 3 is a front elevational view thereof;

FIG. 4 is a rear elevational view thereof;

FIG. 5 is a top plan view thereof; and

FIG. 6 is a bottom plan view thereof.

FIG. 1

FIG. 2

FIG. 3

FIG. 4
